UNITED STATES PATENT OFFICE.

SAMUEL BERGSTEIN, OF MIDDLETOWN, OHIO, ASSIGNOR TO INTERSTATE FOLDING BOX COMPANY, OF MIDDLETOWN, OHIO.

PAPER FOLDING BOX.

Application filed August 10, 1922. Serial No. 580,839.

To all whom it may concern:

Be it known that I, SAMUEL BERGSTEIN, a citizen of the United States, residing at Middletown, in the county of Butler and State of Ohio, have invented certain new and useful Improvements in Paper Folding Boxes and the like, of which the following is a specification, reference being had thereto in the accompanying drawings.

10 This invention relates to improvements in paper folding boxes,—having particular reference to boxes especially adaptable to contain candy, all kinds of small confections and toilet articles, as soap, etc.

15 As here shown, the improved folding box is formed from a one-piece blank, of a suitable design to effect the minimum of waste in cutting the raw stock, and which is adapted to be formed into the finished box 20 entirely by automatic machine operations, thus eliminating hand operations and resulting in a cheaper and better article.

25 While the box as here shown is very similar in appearance and general arrangement to a well-known type of folding box, it has the distinguishing characteristics above referred to—formed from a one-piece blank of novel design—which has the further novel feature of requiring only a single gluing 30 or pasting operation to unite the coacting parts of the assembled box which tends further to simplify and improve the construction.

35 In the accompanying drawings the distinguishing characteristics of the improved box are illustrated in a preferred form of construction,—these features being defined in the appended claims.

In the drawings:

40 Fig. 1 is a diagrammatic view illustrating the design of the paper blank for forming the box, and the manner of cutting the blanks from the raw stock to minimize waste of material;

45 Fig. 2 is a view illustrating the box assembled and folded flat;

Fig. 3 is a view illustrating the box opened ready to have the bottom tucked in;

Fig. 4 is a view of the box closed, and

50 Fig. 5 is a view of the box in cross-section illustrating the foldings of the blank and the reinforced construction.

The blank for forming the box, as here shown, consists of parts —1 and —2 for the sides of the box, parts —3 and —4 for the ends, a flap —5 of part —2 which over-

laps and is glued or pasted to the coacting end —6 of part —4 when the parts are brought together and joined one to the other; parts —3 and —4 are each provided with a flap —7 having scalloped edges —7^a 30 which give an artistic finish to the box and contents when the box is opened,—the flaps also acting to reinforce the lid against pressure of the contents when the box is closed; part —8 which forms the bottom of the box, 35 parts —9 and —10 and part —11 which are tucked in the box as the bottom is assembled therein and serving respectively to reinforce the ends and one side thereof; and part —12 and —13 which form the lid of 70 the box, part —13 being a flap adapted to be tucked in the box on the side opposite part —11 thus acting to further reinforce the construction,—a notch or finger opening —14 being formed in part —1 to provide for convenient withdrawal of flap —13 75 in opening the box.

From the foregoing detailed description and the illustrations, it will be observed that the paper blank for the box is formed of a single piece which is cut from the sheet with the minimum waste of material, and that only the single juncture of parts —5 and —6 requires a gluing or pasting operation to assemble the box; the construction being simple and inexpensive, and the box as a whole being of substantial construction and having a good appearance.

Having described my invention, I claim:

1. A paper folding box, consisting of a one-piece forming blank comprising parts arranged end to end one with another in a strip, the opposite ends of the strip being adapted to be joined one to the other to form the sides and ends of the box, the top and bottom of the box being open, a part attached to one of said side parts, extended laterally at right angles thereof, and having opposite longitudinally extended flaps and a laterally extended flap adapted to be folded and tucked in one of said openings to form the bottom of the box and to reinforce the ends and one side thereof, and a part attached to the other of said side parts, extended laterally at right angles thereof, oppositely of said bottom part, and having a laterally extended flap adapted to be folded and tucked in the other of said openings to form the top of the box.

2. A paper folding box, consisting of a

one-piece forming blank comprising parts arranged end to end one with another in a strip, the opposite ends of the strip being adapted to be joined one to the other to form the sides and ends of the box, the top and bottom of the box being open, an ornamental part attached to each of said end parts, extended laterally thereof and adapted to be folded over the open top of the box, and a part attached to one of said side parts, extended laterally at right angles thereof, and having opposite longitudinally extended

flaps and a laterally extended flap adapted to be folded and tucked in one of said openings to form the bottom of the box and to reinforce the ends and one side thereof, and a part attached to the other of said side parts, extended laterally at right angles thereof, oppositely of said bottom part, and having a laterally extended flap adapted to be folded and tucked in the other of said openings to form the top of the box.

In testimony whereof, I affix my signature.
SAMUEL BERGSTEIN.
